I. L. STEIN,

Steam-Boiler Water-Heater.

N° 22,334.

Patented Dec. 14, 1858.

UNITED STATES PATENT OFFICE.

I. C. STERN, OF PHILADELPHIA, PENNSYLVANIA, ASSIGNOR TO HIMSELF AND GEORGE W. STONE, OF SAME PLACE.

STEAM-BOILER.

Specification of Letters Patent No. 22,334, dated December 14, 1858.

To all whom it may concern:

Be it known that I, ISAAC C. STERN, of the city of Philadelphia and State of Pennsylvania, have invented a new and Improved 5 Mode of Heating Feed-Water for Steam-Boilers; and I do hereby declare the following to be a full, clear, and exact description of the same, reference being had to the accompanying drawing and to the letters of 10 reference marked thereon.

My invention relates to an improvement in the mode heretofore devised of heating the feed water of steam boilers by a system of pipes or tubes, placed in contiguity with 15 the fire, and my improvement consists in placing within the firebox of a locomotive boiler two coils of tubing, one coil being situated on each side, each coil communicating with one of the pumps as well as with 20 the interior of the boiler, the opposite coils communicating with each other, and the whole being arranged substantially in the manner set forth hereafter, so that the cold water from the pumps, prior to its passage 25 into the boiler, may be raised to a high temperature, and obviate the well known injurious effects resulting from the usual mode of injecting cold jets of water into the boilers.

30 In order to enable others skilled in the art to make and use my invention I will now proceed to describe its construction and operation.

On reference to the drawing, which forms 35 a part of this specification, Figure 1, represents an exterior view of an ordinary locomotive steam boiler. Fig. 2, the same with the firebox and a portion of the body in section. Fig. 3, a transverse, sectional elevation on the line 1, 2, (Fig. 2). Fig. 4, an inverted plan view of the firebox.

Similar letters refer to similar parts throughout the several views.

A is the body of the boiler, B the chimney 45 and C the fire-box, all of which may be of the ordinary form and construction.

Two of the ordinary check valves α , and α' are secured one to each side of the firebox, each valve being connected to one of 50 the feed pumps in the usual manner. The force pipe b , from the check valve α , passes through the water space on one side of the fire-box, on the inside of which it assumes the zigzag or coiled form, represented in

Fig. 2, the coil being in close contact with 55 the side of the firebox. The force pipe b' , from the check valve α' , passes through the water space on the opposite side of the firebox, and inside the latter also assumes the form of a coil similar to that on the opposite side. Both coils terminate at, and communicate with the water space of the boiler, the coil b at the point x , and the coil b' at the point x' . A pipe d , fitting against the 60 inside of the firebox, forms a communication between the opposite coils.

As the feed water from the pumps must pass through the whole length of each coil before it can enter the boiler, and as the coil is exposed directly to the fire, it is evident 70 that the temperature of the water must be raised to a degree dependent upon the length of the coil, before it can enter the boiler. The effect of this preparatory heating of the feed water, as a means of economizing the 75 consumption of fuel, is too well known to engineers to require explanation here. It is indispensable that both coils should invariably be filled with water, otherwise the pipes which form the same would be soon 80 destroyed by the action of the fire. The pumps of locomotives being single acting, jets of water are injected into the boiler at rapid intervals, and between these intervals, the coil would be momentarily exposed to 85 the deteriorating action of the fire, were it not for the communicating pipe d . As the pump on one side injects its water at different intervals to that on the opposite side, and as the two coils are connected together 90 by the branch pipe d , it is evident that a free circulation of water will be maintained throughout the interior of both coils as long as the pumps are in operation. When the operation of the pumps ceases, the coils will 95 be filled with water from the boiler and will, consequently, resist the injurious action of the fire.

I do not desire to claim broadly the heating of the feed water, by allowing it to pass 100 through tubes in the fireplace, as such a plan has been heretofore devised; but

I claim and desire to secure by Letters Patent,

The application to locomotive boilers of 105 the arrangement of tubes herein described, that is to say, the arrangement of the coil b or its equivalent on the inside on one side

of the firebox, and the coil *b'* or its equivalent on the opposite side, when one coil communicates with one pump, and the opposite coil with the other pump of the engine, and when the opposite coils are connected together by the pipe *d*, so that the cold water, direct from the pumps may pass into the coils, and thence in a heated state into the boiler, and so that the water may, at all

times, circulate through both coils, as herein set forth.

In testimony whereof I have signed my name to this specification before two subscribing witnesses.

ISAAC C. STERN.
